UNITED STATES PATENT OFFICE.

FRANK W. MERRITT, OF DULUTH, MINNESOTA.

HEATER.

1,393,234.

Specification of Letters Patent. Patented Oct. 11, 1921.

Application filed October 10, 1919. Serial No. 329,675.

To all whom it may concern:

Be it known that I, FRANK W. MERRITT, a citizen of the United States, residing at Duluth, in the county of St. Louis and State 5 of Minnesota, have invented certain new and useful Improvements in Heaters, of which I do hereby declare the following to be a specification.

My invention relates to heaters and has 10 for its object the provision of an improved construction of heater of the type provided with a hard fuel magazine and adapted to heat a current of air or water flowing through passages therefor formed in the 15 walls of the heater. With this and other objects in view, it consists of the structures, combinations and arrangements of parts hereinafter described and claimed.

In the drawings, Figure 1 is a front elevation of my said invention. Fig. 2, is a side elevation thereof. Fig. 3, is a vertical central section on the line A—B of Fig. 1, and on the line A¹—B¹ of Fig. 4. Fig. 4, is a cross section on the line C—D of Fig. 1. 25 Fig. 5, is a vertical central section of the hereinafter described intermediate casting, upon the line E—F of Fig. 4.

In the drawings, 1 is a base, preferably cast, provided with an ash door 1^a, a draft door 1^b and a passage 1^c for grate shaking means, all of any suitable construction. Upon said base is mounted an intermediate casting 2 in which is formed a central fire chamber 2^a, a central fuel magazine 2^b, depending over said fire chamber, an air or water circulation and heating chamber 2^c concentric with said fire chamber and magazine and extending in part over said fire chamber, and a plurality of vertically directed flues 2^d positioned above said fire chamber and extending through said circulation chamber. Extending through the walls of said circulation chamber is a passage 2^e, for the frame 3 of a fire door 3^a of 35 any suitable structure, through which the interior of the fire chamber above the fuel bed may be reached for any desired purpose.

Surrounding the outer side wall of said circulation chamber and spaced therefrom is 40 a casing 4, upon which a preferably cast cover 5 is supported at its circumference, said cover closely encircles the upper end of said magazine and is further supported by said magazine in any suitable manner, as 45 by a collar 2^f formed on the outer wall of the magazine. Said cover is spaced above the

upper ends of said vertical flues, which flues communicate with said space and thereby with the space between said casing and the outer wall of the circulation chamber. 60 Smoke exhaust ports 6 and 6^a extend through said casing, respectively near the upper and lower ends thereof, which ports are adapted to be connected in any suitable manner or by any suitable means (not 65 shown) with a chimney, not shown. Said magazine extends through said cover and is provided at its upper end with a fuel hopper 7 of any suitable structure, which hopper is closed by a lid 7^a of any suitable structure. 70 Erected upon said cover and surrounding said hopper is a removable hood 8. Extending through said cover in alignment with said vertical flues are passages 9 covered by plates 9^a through which passages access 75 may be had to the vertical flues for cleaning the same. Any suitable form or structure of grate may be mounted in said base, as the grate 10. Water or air circulation pipes of any suitable number or structure as 11, 80 12, may extend through said casing and the outer wall of said circulation chamber whereby the heated air or water may be distributed to distant points and the cooled air or water returned to the circulation chamber 85 of the heater.

In operation the chimney draft will be permitted to flow through the port 6 until the fire is well started while the port 6^a will be closed by a suitable damper (not shown). 90 After the fire is well started the chimney draft will usually be permitted to flow through the port 6^a while the port 6 is closed by a suitable damper (not shown). One of the important features of my invention is 95 broadly the form structure and arrangement of said intermediate casting, whereby the walls of the central magazine, and of the flues formed thereon, and of the circulation chamber, and of the fire chamber may all be 100 conveniently and cheaply formed in a single integral casting, and in such manner that a large area of circulation chamber wall is exposed to heat.

Having now described my invention, 105 what I claim is—

1. In a heater, the combination with a suitable base, of an intermediate casting containing a fire chamber, a hard fuel reservoir depending into said fuel chamber, vertically extending radially disposed flues 110 communicating with said fire chamber and

open at their opposite ends, and a fluid conducting chamber surrounding said fire chamber and flues and magazine and extending between said flues to the wall of 5 said fuel reservoir; a casing surrounding said fluid conducting chamber and spaced therefrom, said casing having a smoke exhaust port formed therein; a cover extending from said magazine to said casing, said 10 cover being spaced from said flues, said flues being adapted to communicate through said space with said smoke exhaust port; a grate; and means for covering said magazine.

15 2. An integral structure comprising a fire

chamber and a fuel magazine communicating with said chamber and a plurality of radially disposed flues extending parallel to said magazine and a fluid conducting chamber surrounding said fire chamber and flues, 20 said flues being exterior to said magazine, and the side wall of said magazine being common to said flues and to said fluid conducting chamber.

In testimony whereof, I hereunto affix 25 my signature, in presence of two witnesses.

FRANK W. MERRITT.
